[57] CLAIM

The ornamental design for a hand held skiing stabilizer or similar article, as shown and described.

DESCRIPTION

FIG. 1 is a top plan view of a hand held skiing stabilizer or similar article showing my new design;
FIG. 2 is a bottom view thereof;
FIG. 3 is a front elevational view thereof;
FIG. 4 is a rear elevational view thereof;
FIG. 5 is a side elevational view thereof, the side opposite being substantially a mirror image.

FIG. 2

FIG. 1

FIG. 3

FIG. 4
